UNITED STATES PATENT OFFICE

ONESIME BOISVERT, OF EAST PROVIDENCE, RHODE ISLAND

GUARD FOR PLANING MACHINES

Application filed February 10, 1930. Serial No. 427,333.

This invention relates to improvements in wood working machinery and more particularly to a novel guard for protecting workmen.

5 The principal object of this invention is to provide a collapsible guard for planing machinery which is capable of being constructed to permit displacement of the work.

Another important object of the invention 10 is to provide a guard which because of its collapsible construction, will not be inconvenient in use, and furthermore will not be in the way of the workmen during the operation of the machine.

15 Numerous other important objects and advantages of the invention will become more apparent to the reader after a consideration of the following specification and claims.

In the drawings:—

20 Figure 1 represents a top plan view of a planing machine showing the novel guard in extended position and bearing against work disposed on the machine.

Fig. 2 is a side elevational view of the planing machine equipped with the novel guard.

25 Fig. 3 is a bottom plan view of the guard showing its section in extended position.

Fig. 4 is a bottom plan view of the guard showing the sections in constructed position.

30 Fig. 5 is an elevation of the guard, looking at the free ends of the section and showing the guard in working engagement.

Fig. 6 is a view of one of the intermediate sections of the guard.

35 Fig. 7 represents a fragmentary edge view disclosing the outer section on the latch and the innermost section on the right.

Referring to the drawing wherein like numerals designate like parts, it can be seen in Figs. 1 and 2, that the numeral 5 is a table 40 mounted upon the base structure 6. Upon this table 5 is the fence 7 against which suitable work 8 may bear.

45 Journaled transversely through the base 6 at the upper portion thereof is the drive shaft 9, for the rotary cutter 10. (See Fig. 2.) The shaft 9 projects beyond the rear side of the base 6 and is equipped with a pulley 11 over which the power belt 12 is trained.

50 The novel guard is generally referred to

by numeral 13 and comprises an outer section 14, an inner section 15 and a plurality of intermediate sections *a*, *b*, *c*, and *d*. It will be noted, that the section 14 is sufficiently large to receive not only the section 15, but 55 all of the intermediate sections *a*, *b*, *c* and *d*.

Furthermore the sections graduate in size, the section *a* being sufficiently large to receive the section *b*, the section *b* being sufficiently large to receive the section *c*, *c* to receive *d* and *d* to receive the section 15. 60

It will be noted that the section 15 is stationarily secured to the table 5. Each section has a laterally disposed flange 16 which extends along one longitudinal edge and 65 along its free end. The pivotal end of each intermediate section is provided with an opening 17 for receiving the pin 18 (see Fig. 2).

The outer end of each intermediate section and the section 15 is provided with a longitudinally extending lug 19 which is adapted to abut the inwardly extending lug 20 on the flanges 6 of adjacent sections. 70 This lug 19 is provided on each section, excepting section 14, while the lugs 20 are provided on each section excepting section 15 for abutment with the lugs 19. 75

The pivotal end of the sections 14 and 15, 80 are clearly shown in Fig. 7, wherein the section 14 is provided with a web 21 at the opposite longitudinal edge thereof from the flange 16 and also an intermediate web 22. It can be noted that each of the webs 21 and 22, as well as the flange 16 is provided with an opening 22' for receiving the aforementioned pin 18. 85

The section 15 is provided with apertured webs 23 and 24. The openings in these webs 23 and 24 also receive the pin 18. 90

It can be seen that when all of the sections are connected together, in the manner shown in Fig. 4, they are in interlocked connection, that is, the sections cannot become spaced from each other due to the abutting of the latch 19 against the lugs 20. While the pivotal ends of the sections are connected to the table 5 by the pin 18, the section 15 is secured to the table by disposing a suitable securing element through the apertured ear 95 25

at its free end. To maintain the outermost section 14 tensionally against the work, leaf springs 26 are interposed between the flanges at 16, so that they will normally assume the extended position shown in Fig. 3.

As the guard expands over the cutter 10 in the manner shown in Fig. 1, there is very little possibility of any workmen injuring themselves accidentally through the agency of the cutter 10.

While the foregoing description specifically sets forth the details making up this invention, it is to be understood that certain changes may be made in the shape, size, and materials without departing from the spirit and scope of the invention as claimed hereininafter.

Having thus described my invention, what I claim as new is:—

- 20 1. A guard for the blades of cutting machinery, comprising a plurality of pivotal plates, said plates being pivotally connected together each at one of its ends, flanges on the longitudinal edges of the plates, and leaf springs interposed between the said flanges, so as to maintain the plates in extended relation with respect to each other.
- 25 2. A guard for the blades of cutting machinery, comprising a plurality of pivotal plates, said plates being pivotally connected together, each at one of its ends, flanges on the longitudinal edges of the plates, leaf springs interposed between the said flanges, so as to maintain the plates in extended relation with respect to each other, and abutting lugs on the free ends of the said plates to limit their extended relation.

In testimony whereof I affix my signature.
ONESIME BOISVERT.
